UNITED STATES PATENT OFFICE.

FREDERICK E. WALDEN, OF WORCESTER, MASSACHUSETTS, ASSIGNOR TO BAY STATE TOOL COMPANY, OF BOSTON, MASSACHUSETTS, A CORPORATION OF MAINE.

WRENCH OR THE LIKE.

SPECIFICATION forming part of Letters Patent No. 761,798, dated June 7, 1904.

Application filed September 4, 1903. Serial No. 171,876. (No model.)

To all whom it may concern:

Be it known that I, FREDERICK E. WALDEN, a citizen of the United States, and a resident of Worcester, in the county of Worcester and State of Massachusetts, have invented new and useful Improvements in Wrenches or the Like, of which the following is a specification.

My invention relates to hand-tools, particularly to wrenches and like articles; and the object of my invention is to provide a simple and easily-operated wrench whose two jaws may be adjusted and fixed in relative position with ease and rapidity.

In accordance with my invention the wrench or the like comprises a movable jaw, a fixed jaw having a stem or the like on which the movable jaw is mounted, a toothed bar on one side of the jaws, and a toothed socket on the other jaw, said bar and socket being each made with a longitudinal passage-way for the tooth or teeth of the other and relatively rotatable to engage and disengage them to lock the movable jaw to the fixed jaw or free it therefrom.

In the preferred form of my invention the socket is on the movable jaw and the bar is a rock-bar journaled near one end on the stem of the fixed jaw, the other end of the rock-bar extending into the socket on the movable jaw. On the rock-bar near the outer end of the stem is provided a thumb-piece through which the rock-bar can be operated to engage or disengage the socket.

In the accompanying drawings, Figure 1 is an elevation of a wrench embodying one form of my invention. Fig. 2 is a similar view partly in section. Fig. 3 is a cross-sectional view of the rock-bar hereinafter described. Fig. 4 is a cross-sectional view of the movable jaw of the wrench shown in Figs. 1 and 2. Fig. 5 is a section on line 5 5 of Figs. 1 and 2.

Herein I have embodied my invention in a wrench, and in the accompanying drawings A represents one of the jaws of the wrench, which, for convenience, I have designated the "fixed" jaw, said jaw being provided with a stem *a*,

terminating in a handle *a'*. On the stem *a* is mounted jaw *B*, made with a socket *b* parallel with the stem *a* and provided with two rows of diametrically-opposed segmental teeth *b'*, separated by two longitudinal passage-ways *b''*. Into the socket *b* extends a rock-bar *C*, made with two diametrically-opposed rows of segmental teeth *c*, separated by two longitudinal passage-ways *c''*. The width of each longitudinal passage-way *b''* and *c''* is slightly greater than the width of the teeth *c* and the width of the teeth *b*, so that by rocking and positioning the rock-bar *C* the latter may be thrown into and out of engagement with the socket *b*—that is, when the rock-bar *C* is in one angular position it is free to move relatively in and out of the socket *b* of the movable jaw *B*, and when in another angular position it is locked against relative longitudinal movement. Fig. 4 shows by dotted lines the position of the rock-bar *C* when jaw *B* is free to be moved on stem *a*, and Fig. 1 shows the position of rock-bar *C* when jaw *B* is locked in position on stem *a*.

The outer end of the rock-bar is journaled in a bracket *a²*, fixed to stem *a*, and said rock-bar extends through this bracket into a pocket *a³*, provided in handle *a'*. Between bracket *a²* and pocket *a³* rock-bar *C* is provided with an arm on thumb-piece *c'*, by means of which the user of the wrench can operate the rock-bar *C*. Normally rock-bar *C* is held with its teeth *c* in engagement with the teeth *b'* of socket *b* by a spring *c²*, arranged within the pocket *a³* and fastened at one end to handle *a'* and at its other end to the rock-bar *C*. When the user presses thumb-piece *c'* down to free the movable jaw, spring *c²* is put under tension, and when pressure is relieved from thumb-piece *c'* spring *c²* returns the rock-bar to normal position. The engagement of thumb-piece *c'* with the bottom of pocket *a³* serves to limit the extent of movement of rock-bar *C*, when it is thus depressed by the user to free the movable jaw *B*.

It will now be observed that the movable jaw *B* is normally locked in position on stem

a, but that by a slight movement of the thumb-piece *c'* the jaw is quickly freed, and may be adjusted longitudinally of the stem *a* to any desired position quickly and with ease.

- 5 The socket *b* in jaw *B* is preferably made by first tapping said socket and then cutting it out at two opposite points, so as to provide the passage-ways *b''* between the two rows of teeth *b'*, while the rock-bar *C* is made by first 10 threading that bar with threads of the same pitch as those in socket *b*, and then cutting away those threads, so as to provide the passage-ways *c''*. The advantage derived from producing the teeth in this manner—that is, 15 with a pitch—is that when spring *a''* returns rock-bar *C* to normal position after jaw *B* has been adjusted on the stem *a* the thread-like teeth of the bar tend to press the movable jaw farther toward the fixed jaw, and this effect 20 may be enhanced by the user supplementing the pressure of spring *c''* by thumb-pressure.

It will thus be seen that when the tool is used upon a nut, for example, and the jaws have been adjusted as close as possible while 25 unlocked a final pinch, so to speak, will be given by the locking of the jaws.

As shown in the drawings, the teeth *c* on rock-bar *C* are made from a left-hand thread, and those within socket *b* correspond. The 30 reason for this is that it is more convenient to have the thumb-piece *c'* throw down at the right-hand side of the handle *a'* than at the left; but of course the direction of the thread can be suited to the direction in which rock-bar *C* moves when the thumb-piece is depressed. It is understood, however, that it is 35 not essential to my invention that there be any pitch to the teeth *b'* and *c*, and that the

number of rows, form, and number of teeth can be widely varied.

40

What I claim is—

1. A wrench or the like comprising a movable jaw; a fixed jaw having a stem or the like on which the movable jaw is mounted to slide to and from the fixed jaw; a toothed rock-bar 45 journaled near one end on the stem of the fixed jaw; a thumb-piece on the rock-bar for turning the rock-bar in one direction; a spring for turning the rock-bar in the opposite direction; and a toothed socket on the movable 50 jaw, said rock-bar and socket being each made with a longitudinal passage-way for the tooth or teeth of the other and relatively rotatable to engage or disengage them to lock the movable jaw to the fixed jaw or free it therefrom. 55

2. A wrench or the like comprising a movable jaw; a fixed jaw having a stem or the like on which the movable jaw is mounted to slide to and from the fixed jaw; a threaded rock-bar journaled near one end on the stem of the 60 fixed jaw; a thumb-piece on the rock-bar for turning the rock-bar in one direction; a spring for turning the rock-bar in the opposite direction; and a threaded socket on the movable jaw, said rock-bar and socket being each made 65 with a longitudinal passage-way across its threads for the threads of the other relatively rotatable to engage or disengage them to lock the movable jaw to the fixed jaw or free it therefrom.

Signed by me at Boston, Massachusetts, this 29th day of August, 1903.

FREDERICK E. WALDEN.
